UNITED STATES PATENT OFFICE

ISAË CLÉMENT FRANÇOIS ADAM, OF PARIS, AND RENÉ ALEXIS RAGODY, OF LE PERREUX, FRANCE, ASSIGNORS TO COMPAGNIE FRANÇAISE DES APPAREILS ADAM, OF PARIS, FRANCE, A LIMITED COMPANY OF FRANCE

APPARATUS FOR THE PERMANENT WAVING OF THE HAIR

Application filed December 17, 1928, Serial No. 326,860, and in France December 22, 1927.

The present invention has for object an apparatus which allows of obtaining, on a head of hair of variable length, an artificial waving of long duration, so-called permanent waving, having the appearance of a natural waving.

This apparatus applies the known general principle according to which the waving of a lock of hair is obtained by rolling it up on 10 a hair curler after having previously spread it in the form of a sheet or layer of approximately uniform thickness and of variable width according as it is examined at the point or at the root of the hair; and by heating it 15 after having impregnated it with a suitable solution.

The apparatus forming the subject-matter of the invention presents, relatively to the known apparatus which apply the above principle, the main following advantages:

(1) The tension of the hair, from which depends the permanence of the waving, is adjustable, at the will of the operator and cannot get out of adjustment independently of 25 the will of the latter.

(2) The tension of the hair is as great as may be desired by the operator, this tension not being exerted on the root of the hair.

(3) It constitutes a practically fluid-tight 30 structure which communicates with the exterior only through an orifice situated in such a place that the vapour evolved may not burn the scalp; it allows also to dispense with the auxiliary protecting means: calico, flannel, 35 paraffined paper, etc.; the protection of which is of little efficiency and the use of which renders long and tedious the preparation of the waving.

(4) Its shape, its fluid-tightness and the 40 location of its heating apparatus reduce to the minimum the heat losses and, consequently the time necessary for obtaining a satisfactory waving.

The accompanying drawings illustrate, by 45 way of example only, two forms of construction of the apparatus forming the subject-matter of the invention.

Figures 1 to 9 relate to a first form of construction and are:

50 Figure 1 a sectional view of a hair curler.

Figure 2, a sectional view according to line CC of Fig. 4 of a stove, of which Figs. 3 and 4 are respectively an elevation and section, and a plan view of a jaw, and Figs. 5 and 6, a cross section and a partial horizontal section.

Figure 7 is a view in elevation of a preparation slip.

Figures 8 and 9, cross sections according to A—A and B—B of Fig. 7, respectively.

Figures 10 to 16 relates to a second form of construction.

Figures 10 and 11 show a hair curler, in elevation and in plan view, respectively.

Figure 12 is, on an enlarged scale, a cross section of the stove, according to D—D of Fig. 14.

Figure 13 is a longitudinal section of the stove in its entirety.

Figure 14 is a top plan view of the lower jaw of the stove;

Figure 15 is an elevation of the clip in closed position.

Figure 16 is a partial side view, with cross section, of the clip and of the hair curler mounted in the supports of the latter.

In the example of construction illustrated in Figs. 1 to 9, the apparatus comprises:

(1) A hair curler (Fig. 1) the central portion 1 of which is constituted by a solid of revolution generated by the rotation of a curve about the axis α α' of the hair curler and the end parts 2 and 2' by two cylinders of revolution terminated by two frustum-shaped nipples receiving the obturating tubes 3 and 3'. The end 2 is provided with a series of recesses 2^a which constitute the female part of a retaining pawl and ratchet device to be described later on, and a slot 4 for receiving a tool such as a bent screw driver which allows the hair curler to be rotated when it is mounted in the stove. The central portion of the hair curler is provided with a spring 5 adapted to retain the hair at the beginning of the rolling up operation.

(2) A stove (Figs. 2 to 6), electrically heated and constituted by two jaws 6 and 6' connected by a bolt 7 or any other tightening device and compressing between their edges an obturating packing 8. On each of their

faces adjacent to the scalp, these jaws are provided with plates 9 and 9' which are non-conductor of heat and adapted to protect the head against heat. Each jaw has two bearing portions 10 and 10' for the ends 2 and 2' of the hair curler. One of the jaws receives the pawl of a pawl and ratchet device constituted by a ball 11 (Figs. 2 and 6) returned by a spring 12 which presses on a threaded plug 13. The ratchet of the pawl and ratchet device, is constituted by the part 2 having recesses 2^a (Fig. 2). Within the stoves are placed electric resistances 14 (Figs. 5 and 6). The resistances 14 are in the shape of coils supported in a double trough 14' fastened by screws 6'' upon internal bosses of the shell or jaw 6. Two connecting rods or plugs 6^a allow to feed electric current into the resistances from any suitable electric conductors wires. Upon passage of an electric current, is delivered the heating necessary for the waving. The plugs 6^a secured on the jaws 6 or connected to the latter as in the known apparatus, so that the weight of the stove is balanced by a counter-weight or by the tension of a spring and through the medium of the wire conveying the electricity.

(3) A preparation clip (Fig. 7) which carries two jaws 15 and 15' jointed at one of their ends and capable, at the other end, of being locked by a lever 16 pivoting about an axis rigid with the jaw 15. One of the jaws of the clip is provided with two arcuated supports 17 and 17' acting as springs and adapted to receive, at the end of the rolling up operation, the ends of the hair curler. One of these supports has a projection 18 adapted to enter the recesses 2^a of the hair curler for immobilizing the latter when the rolling up operation is finished.

The apparatus, in the form of construction which has just been described, is used in the following manner:

A lock of hair is separated and grasped near the scalp with the preparation clip; the latter is tightly closed and the hair is engaged under the spring of the hair curler, the lock of hair is rolled up by hand by spreading it in the form of a layer of approximately uniform thickness and, at the end of the rolling up operation, the hair curler is placed in the supports 17, with the projection 18 fitted into one of the recesses 2^a of the hair curler. As many hair curlers as the head of hair has locks of hair are prepared in the same manner.

The jaw of the stove provided with the pawl 11 is placed in position and the said pawl is inserted in a recess of the hair curler by holding the latter in the hand; the clip is removed and the second jaw is placed on the first one by locking the nut 7. The hair, being clamped between the edges of the jaws 6 and 6', is stretched by causing the hair curler to rotate in the direction for clamping by

means of the bent screwdriver or of any other tool. The ball 11 allows, if need be, to turn the curler back, when the operator has stretched the hair too strongly.

This operation is repeated for all the stoves. 70

Heating is effected by causing the current to pass during the required time, which varies according to the texture of the hair.

The jaws are then withdrawn; the hair curler is removed and the hair is washed and 75 combed.

In the example of construction illustrated in Figs. 10 to 16, the hair curler (Figs. 10 and 11) has a central portion 1 with a spring 5 the shape and function of which are substantially those already indicated with reference to the first form of construction. But the cylindrical parts 2 and 2' which are centered in bearing portions of the stove, are terminated by cylindrical bosses 4 and 4' the main function of which is indicated later on and which are axially slotted or prepared in any other manner for being engaged by a tool for stretching the lock of hair. Between the body 1 and the trunnions 2 and 2' are interposed flanges 3^a which exactly determine the transverse position of the hair curler in the stove, as shown in Fig. 14. 85

The end 2 is provided, as in the preceding example, with recesses 2^a which, in combination with the pawl of the stove, allow to ensure and maintain the tension of the hair. 90

The stove (Figs. 12, 13 and 14) has two jaws 6 and 6' connected by a screw 7, the longitudinal displacement of which relatively to the jaw 6 is limited by a ring 7' or any other equivalent stop device. 100

The screw 7 cannot, from this fact, abandon the jaw 6 and be misled. It is screwed in a fixed nut 7^a of the jaw 6' for ensuring the closing of the stove; a packing 8 is, as in the first example of construction, interposed between the adjacent edges of the jaws 6 and 6'. 110

An axis 7^b, screwed for instance in the nut 7^a, constitutes a pivot for a shutter 7^c provided with an operating lug 7^d and which covers or uncovers a port 7^e formed in the wall of the jaw 6'. This port allows the passage to the exterior of the stove of the end portion of a lock of hair when it is desired to shelter from the heat the said portion whatever may be its length. 115

One of the jaws of the stove receives the stop pawl of the hair curler. This pawl (Fig. 12) is a sliding finger 1 returned by a spring 10 which bears on an obturator 12 held by a pin 13. Within the stove are arranged heating resistances 14. 120

One of the jaws of the stove has a perforated screen or grid 15' adapted to protect the hair against a too rough action of the source of heat. The jaws 6 and 6' are, moreover, provided, on a portion of their outer faces, with coatings 6^a and 6'^a which are not conductors of heat and are adapted 130

to render the manipulation of the same more easy and to reduce to the minimum the heat losses.

The clip for preparing the locks of hair to be waved (Fig. 15) differs from that already described, particularly in that the jointing face of the jaws 15 and 15' has a shoulder at its central portion. The jaw 15' is provided, for that purpose, with a tenon 5 or projection 15^a which, when the clip is closed, fits in a corresponding slit and tongue joint of the jaw 15. The lock of hair is spread in the form of a sheet in the slit and tongue joint and cannot, from this fact, disperse throughout the width of the clip. It 10 is thus spread on a length which corresponds to that it must occupy on the hair curler. The clip is held closed by the pressure exerted, on one of its jaws, by a finger 19 arranged 15 at the end of a spring or resilient blade 20 secured on the other jaw, at the end opposite the hinge 21.

One of the jaws of the clip is provided with two preferably resilient supports 17 and 25 17' adapted to receive the ends 4 and 4' of the hair curler. These supports can have two small tenons 21 and 21' which fit in the grooves of the cylindrical portions 4 and 4' of the hair curler and prevent the rotation 30 of the latter after it has been placed in position on the clip and during the period of preparation. The face of the jaws 15 and 15', on the side opposite to the supports 17 and 17' of the hair curler, is conveniently 35 lined with an insulating packing 22 and 22' composed of one or more thicknesses of material which are nonconductors of heat, permanently secured in position and adapted to protect the scalp against the heat evolved 40 from the stove.

The apparatus, in the form of construction which has just been described, is used as follows: A lock of hair is separated and grasped near the scalp with the preparation 45 clip, taking care to insert the lock of hair in the housing provided for receiving it on the clip. The latter is locked and the lock of hair is moistened with a suitable liquid, or, on the rolled up hair, is placed a small bag 50 of suitable composition, this operation taking place at the time the hair curler is inserted between the jaws of the stove. The hair curler is taken hold of by engaging the hair under the spring 5 at the place where it is 55 desired the waving should begin. The lock of hair is then rolled up on itself by hand by giving to the layer of hair a nearly constant thickness and, at the end of the rolling up operation, the hair curler is placed in the 60 resilient supports 17 and 17' of the clip, so that the tenons 21 and 22 of the said supports fit into the grooves of the ends of the hair curler.

The head curler is placed in position on 65 the jaw of the stove which has a port 7^c

through which is inserted the portion of the lock of hair not rolled up on the hair curler and which must not be waved; it is ascertained if the shutter 7^c is in closing position and the other jaw is placed in position. The locking screw 7 is tightened after ascertaining if the pawl 11 is really fitted into a recess 2^a of the hair curler.

The hair being clamped between the edges of the jaws, it is stretched by causing the hair curler to turn in the direction for clamping by means of a screw-driver or of any other suitable tool. The operation is terminated as already explained.

What I claim as my invention and desire to secure by Letters Patent is:—

1. In an apparatus for the permanent waving of hair of the character described, in combination: clips provided with means for supporting a hair curler, a heating stove formed by two shells which are superposed on their edges so as to form between them a heating chamber, electric heating resistances in one of the shells, in the rear part thereof, semi-cylindrical bearings on the lateral edges of the said shells for forming bearing supports of the curler in the front part of the shells, means on the ends of the curler for ensuring the tightness of the stove and recesses in the curlers and a spring returned pawl on the stove and having a spherical end to engage spherical recesses in the curled and means for maintaining the shells relatively to each other.

2. In an apparatus for the permanent waving of hair of the character described, in combination: clips having curved pieces of metal on one of their branches for supporting a curler, a heating stove formed by two shells which are superposed on their edges, electric heating resistances placed in one of the shells, in the rear part thereof, semi-cylindrical bearings on the lateral edges of the said shells for forming bearings for a curler, tightening means on the ends of the said curler, recesses in the curler and a spring returned pawl in the interior of one of the semi-cylindrical bearings of the shells and having a spherical end for engaging spherical recesses in the curler, a grid fixed on one of the said shells between the seat of the curler and the heating resistances and means for maintaining the shells relatively to each other.

3. In an apparatus for the permanent waving of hair of the character described, in combination: clips having curved pieces of metal on one of the branches of the clips for supporting a curler, a heating stove formed by two shells which are superposed on their edges, electric heating resistances placed in one of the shells in the rear part thereof, semi-cylindrical bearings on the lateral edges of the said shells for forming supports for a curler, tightening means on the ends of the said curler, a spring returned pawl in one of

the shells of the stove, and having a spherical end for engaging spherical recesses in the curler, a grid fixed on one of the said shells between the seat of the curler and the electric 5 heating resistances, a screw and nut connection between the shells for maintaining same relatively to each other, a shutter pivoted to one of the shells for controlling an opening in the bottom of the said shell.

10 In testimony whereof we have signed our names to this specification.
